PIPE TONGS

John Claud Green, Dubach, La., assignor of one-third to Thomas L. Owen, Dubach, La.

Application October 28, 1930. Serial No. 491,775

1 Claim. (Cl. 81—70)

This invention appertains to wrenches and more particularly to wrenches of the type particularly adapted for use on round work, such as pipes and the like.

5 One of the primary objects of my invention is to provide a pipe wrench or tongs comprising rigid jaws for engaging one side of the work, and a flexible chain for engaging about the work, with novel cooperating means carried by the chain and jaws for adjustably locking the chain with the jaws.

Another salient object of my invention is to provide a reversible pipe wrench or tong of the chain type, that is a wrench which can be utilized for turning the work both in a clockwise and counter clockwise direction, the wrench including a rigid jaw for engaging one side of the work having oppositely directed teeth arranged on an inclined plane, with a chain for engaging about the work pivotally connected to the rigid jaw intermediate the ends thereof and substantially at the point of meeting of the oppositely directed teeth, the jaw carrying means for locking the chain in an adjusted position.

25 A further important object of my invention is the provision of novel means for forming the rigid jaw and novel means for connecting the locks for the chain with the rigid jaw.

A still further object of my invention is to provide a pipe wrench of the above character, which will be durable and efficient in use, one that will be simple and easy to manufacture, and one which can be placed upon the market at a reasonable cost.

35 With these and other objects in view, the invention consists in the novel construction, arrangement and formation of parts, as will be hereinafter more specifically described, claimed, and illustrated in the accompanying drawing, in

40 which drawing:

Figure 1 is a side elevation of my improved wrench, showing the chain placed about the work.

Figure 2 is a top plan view of the wrench showing parts thereof broken away and in section.

Figure 3 is a transverse section through the wrench taken on the line 3—3 of Figure 1 looking in the direction of the arrows.

50 Referring to the drawing in detail, wherein similar reference characters designate corresponding parts throughout the several views, the letter A generally indicates my improved pipe wrench or tong, which includes an elongated handle 5, having its forward end terminat-

ing in a head 6. The rear end of the handle can be provided with any preferred type of grip plates 7, formed of leather, wood, rubber, or the like.

The opposite sides of the head 6 are recessed as at 8, for receiving the shank portions 9 of the jaw plates 10 and 11. These jaw plates are arranged in spaced parallel relation to one another and are of a substantially diamond shape in side elevation. The upper edges of the jaw plates 10 and 11 adjacent to the inner ends thereof and in rear of the transverse center thereof is provided with a bridge block 12 and this block is held in place by removable bolts 13 passing through the depending portion of the bridge block 12 for securing the bridge block firmly between the jaw plates 10 and 11. This bridge block 12 overhangs the upper edges of the jaw plates 10 and 11 as shown in Figure 2, for the purpose of relieving strain from the removable bolt 3 and permitting the upper edges of the jaw plates 10 and 11 to take up the strain placed upon the holding chain 17. The outer face of the bridge block is provided with a pair of spaced hooks 14, which form a lock for the holding chain 15. One end of the chain is left free and the opposite end of the chain is pivotally connected to the jaw plate 10 and 11 by means of a pivot bolt 15', which is arranged adjacent to the upper surface of the jaw plate substantially at the transverse center thereof. The chain 15 is of substantially the sprocket type and includes the links 16 pivotally connected together by pivot pins 17, which extend beyond the links. The links are adapted to be received between the hooks 14 and the terminals of the pivot pins seat in the bill of the hook to bring about the locking engagement of the chain with the jaw plates.

The lower edges of the jaw plates 10 and 11 incline upwardly in opposite directions to form the substantially diamond shape of said jaw plates and these lower edges are provided with oppositely directed bighting teeth 18 and 19.

In use of my improved wrench or pipe tongs the jaw plates are placed over or in engagement with the round work and the chain 15 is brought about the same and the free end of the chain is brought between the jaw plates and the adjacent pivot pins 17 of the chain is received in the bill of the hooks 14.

The work can now be swung on either side of the transverse center of the jaw plates for engagement either with the teeth 18 or 19, and thus the work can be readily turned either in a

clockwise or counter clockwise direction. Thus I have provided a wrench of a substantially reversible nature in that the work can be freely turned either one way or the other.

8 5 From the foregoing description, it can be seen that an exceptionally simple and durable pipe wrench has been provided in which the work will be effectively gripped and in which a greater leverage can be obtained thereon.

10 The block 12 can be readily removed when worn by merely removing the bolt 13 and thus this block can be readily and easily replaced when necessary or desirable.

15 Changes in details may be made without departing from the spirit or the scope of this invention, but:—

What I claim as new is:

18 A wrench for round work comprising a handle, a plurality of spaced rigid jaws fixedly secured 20 to said handle, said jaws being provided with upwardly inclined lower edges and upper inclined edges, oppositely directed ratchet teeth

formed upon said lower edges, a gripping chain, a pivot bolt connecting one end of said gripping chain to the jaws substantially at the meeting point of the upper inclined edges of the jaws, a removable bolt carried by the jaws, said pivot bolt being mounted in the rear of said removable bolt whereby the free end of said gripping chain when secured will overhang said pivot bolt, a bridge block having a depending portion extending between said jaws, said removable bolt engaging said depending portion and fixedly securing said bridge block between the jaws, said bridge block overhanging the upper edges of said jaws and provided with a pair of spaced hooks upon the upper face thereof, said gripping chain adapted to pass between the jaws and fit over the top of said bridge block and engage said hooks for detachably securing the chain to said bridge block, the overhanging bridge block being adapted to transmit the strain from the chain to the top edges of said spaced jaw plates.

JOHN CLAUD GREEN.
